CLAIM

I claim the ornamental design for a ceiling fan, as shown and described.

DESCRIPTION

FIG. 1 is a bottom perspective view of a ceiling fan showing my new design.

FIG. 2 is a top perspective view of the ceiling fan of FIG. 1.

FIG. 3 is a top plan view of the ceiling fan of FIG. 1.

FIG. 4 is a bottom plan view of the ceiling fan of FIG. 1.

FIG. 5 is a side elevation view of the ceiling fan of FIG. 1.

FIG. 6 is another side elevation view of the ceiling fan of FIG. 1; and,

FIG. 7 is a plan view of a fan blade of the ceiling fan of FIG.

1 shown separately for completeness of illustration.

The broken lines on the drawings depict portions of the ceiling fan that form no part of the claimed design.
